TOOTHBRUSH

Aaron House Brennesholtz, Ridgewood, N.J., assignor to
E. I. du Pont de Nemours and Company, Wilmington,
Del., a corporation of Delaware

Filed July 29, 1963, Ser. No. 75,999

Term of patent 14 years

(Cl. D9—2)

FIG. 1

FIG. 2

FIG. 4

FIG. 5

FIG. 3

FIGURE 1 is a rear elevational view of a toothbrush showing my new design.

FIGURE 2 is a side elevational view thereof.

FIGURE 3 is a front end view thereof.

FIGURE 4 is a cross-sectional view of the toothbrush of FIGURE 1 taken on the lines 4—4 of FIGURE 1.

FIGURE 5 is a cross-sectional view of the toothbrush of FIGURE 1 taken on the lines 5—5 of FIGURE 1.

The dominant features of my design reside in the portions shown in full lines.

I claim:

The ornamental design for a toothbrush, as shown and described.
